UNITED STATES PATENT OFFICE.

LOUIS ZIMMER, OF PITTSBURG, PENNSYLVANIA.

CARPET AND OIL-CLOTH STRETCHER.

SPECIFICATION forming part of Letters Patent No. 232,099, dated September 7, 1880.

Application filed July 24, 1880. (No model.)

To all whom it may concern:

Be it known that I, LOUIS ZIMMER, a citizen of the United States, residing at Pittsburg, in the county of Allegheny and State of Pennsylvania, have invented certain new and useful Improvements in Carpet and Oil-Cloth Stretchers; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 This invention relates to that class of improvements known as "carpet and oil-cloth stretchers," and used in stretching carpets upon floors preparatory to tacking or otherwise securing the same in place; and it consists in 20 the combination of two gripping-jaws provided or pivoted in the lever, the whole so arranged and constructed that the jaws will automatically open or close by means of the operation of the lever, as will be hereinafter more fully 25 described, and pointed out in the claims.

A designates the lever, with its upper end provided with a hollow handle for the reception of an adjustable lever or handle, a^2 , and at the lower or pointed end, a' , is made so as 30 to afford a good hold upon the floor while the operator is stretching and holding the carpet. In the center of the lever A is formed a slot, a , with holes for the reception of the pin b^3 , which enters and holds the blades of the slot-

ted arms b b , to operate either in closing or 35 opening the said jaw-arms.

B B are the jaw-arms, provided at one end with the jaws b' and at the other end with the slot b , which receives and has its bearing on the pin b^3 , as shown in Figs. 1 and 2 of the 40 drawings. That portion of the jaw-arm which is slotted is curved or bent in opposite directions to each other, thus allowing the blade-arms to operate in opposite directions when being opened and in closing to reverse its 45 motion.

Having thus fully described my invention, what I claim as new, and desire to secure by Letters Patent, is—

1. The lever A, provided with a slot, a , for 50 the reception and guidance of the jaws B, substantially as and for the purpose set forth.

2. The jaw-arms B, provided with the bent slotted arms b b , all constructed and arranged to operate in the manner shown and described. 55

3. In a carpet-stretcher, the lever A, in combination with the automatic jaw-arms operating within the recess a of the lever, said arms slotted at one end thereof, as shown and described, and for the purpose set forth. 60

In testimony whereof I herewith affix my signature in presence of three witnesses.

LOUIS ZIMMER.
